FIBER TREATMENT

Sverre Gulbrandsen, Gloucester, N. J., assignor
to New Process Rayon, Inc., Gloucester, N. J.,
a corporation of Delaware

Application June 11, 1937, Serial No. 147,607

1 Claim. (Cl. 8—151)

The present invention relates in general to apparatus and method for the bath treatment of textile material, and in particular to apparatus and method for the bath treatment of relatively high denier, continuous filament, rayon roving.

The chief objects of the invention are the provision of an apparatus and method for thorough bath treatment such as chemical treatment, washing, soaping, etc., the saving of time in such treatments, and the saving of space occupied by the necessary apparatus.

Other objects and advantages of the invention will be apparent from a perusal of the following specification and the drawing accompanying the same.

In the drawing:

Fig. 1 is a side view showing the apparatus arrangement submerged in a treating bath.

Fig. 2 is a similar view on a small scale illustrating a modified method of operation.

Fig. 3 is a diagram showing the relative skew arrangement of the rollers.

Referring to the drawing in detail and first to Fig. 1 which is diagrammatic of the cooperative relation of the apparatus elements, 10 and 11 are representative of a pair of upper and lower guide rolls arranged to guide a roving 12 of the material to be treated on to and several times around the rolls while submerged in a suitable treating bath 13, the rolls 10 and 11 being arranged slightly askew relative to each other or canted, in well-known manner to effect a feeding of the roving axially along the rolls as indicated in Fig. 3 where the canting is shown considerably exaggerated for the sake of clearness.

The lower roll 11 is completely submerged in the bath 13 while the upper roll 10 is submerged sufficiently to maintain the roving within the bath where it leads and enters upon the roll in its movement through the bath.

Intermediate between the upper and lower rolls are pairs of squeeze-rolls 14—15 and 16—17 arranged to receive the roving 12 in wringer-like operative engagement therewith as shown for squeezing the filaments of the roving together during the passing of the roving through the bath. The roving 12 is moved or propelled through the bath preferably by driving the upper roll 10, traction between the squeeze-rolls and the roving being prevented by driving one or both of said rolls with a peripheral velocity equal to or substantially equal to that of the roving and in the same direction as the roving. As one way of driving the squeeze-rolls and driving roll 10 at the same peripheral velocity, the squeeze-rolls

may derive their motion from the feed roll 10 through a suitable idler gear.

In operation, with the apparatus elements arranged as shown and a continuous roving loaded on to the rolls for movement into, through and out of the bath as indicated by the arrows adjacent to the roving, rotation of the roll 10 will cause the roving to move continuously through the bath several times around the rolls and then out of the bath, passing between the squeeze-rolls in both its downward and upward drive between the top and bottom rolls. During its passage through the squeeze rolls, the filaments of the roving will be squeezed together driving out the bath solution from between the filaments and will be released again upon movement of the roving out of engagement with the squeeze rolls to permit re-entrance of the bath between the filaments of the roving. It will thus be clear that this repeated squeezing together and releasing of the filaments during the passage of the roving through the bath results in an acceleration of the interchange of contact between the filaments and the bath whereby the time required for a given amount of interchange or bath treatment is greatly reduced over that which would be required were the roving simply moved through the bath without such repeated squeezing and releasing of the filaments. Inasmuch as it is preferable to drive the squeeze-rolls in order to prevent relative movement between them and the roving it is possible, and may in some cases be preferable to use the squeeze-rolls as the means for propelling the roving through the bath, in which case the rolls 10 may be driven from the squeeze-rolls either through the gear 18 or by frictional engagement of the roving 12 therewith.

To further accelerate the rate of interchange of contact between the bath and the filaments, the roving may be loaded onto the rolls 10 and 11 and through the squeeze-rolls with a slight tension between the points where the roving leaves one of the main rolls and passes between a pair of the squeeze-rolls, and to leave considerable slack between the points where the roving leaves a pair of the squeeze-rolls and contacts with one of the main rolls, as shown in Fig. 2. Once this arrangement of relative slight tension and ample slack is established, with the various rolls positively driven at substantially equal peripheral velocity, such condition will be maintained indefinitely. One way of establishing such condition is to first load the roving onto the rolls in any known or other suitable manner as by drawing it through on the end of a pilot tape or rope, and after the

loading is completed, to drive the squeeze-rolls a little faster than the main rolls 10 and 11 for a brief period of time or to rotate the squeeze-rolls a slight amount with the main or guide rolls 5 10 and 11 held stationary. It is to be understood, of course, that at any point the tension is very slight and need only be sufficient to effect a guiding of the roving around the main rolls 10 and 11. However, this very slight tension is sufficient to keep the filaments of the roving in substantial parallelism and sufficiently free of each other to permit flow of the bath solution therebetween, while the positive feed or propulsion of the roving toward the main rolls 10 and 11 will 10 15 tend to maintain any previously established slack between the esqueeze-rolls and the main roll in the direction of movement of the roving, permitting the individual filaments of the roving to spread apart with considerable freedom of lateral motion 20 as they are moved through the bath toward the main rolls.

While the invention herein disclosed finds its greatest usefulness in the continuous submerged bath treatment of relatively high denier, continuous filament rayon yarns or roving, with little or no twist, it will be clear that an application of 25 the present invention will be very useful in the

treatment of any kind of textile material in the form of a continuous roving or yarn even though slightly twisted, and makes for the advantage of increased efficiency of treatment with reduction of time required and a saving of space. 5

While I have thus shown and described a specific embodiment of my invention and a specific mode of carrying out the method involved, it is to be understood that the invention is not limited to such examples of application of the invention 10 but contemplates all such modifications and variations thereof as fall fairly within the scope of the appended claim.

What I claim is:

The method of bath treating a relatively high 15 denier, continuous-filament, rayon roving which comprises, while moving the roving through a bath, subjecting successive portions of the roving to a slight tension sufficient to bring the filaments in said successive portions into substantial 20 parallelism thereafter squeezing the filaments together to expel a portion of the bath from between them, and thereafter producing a slack in the filaments to permit them to float loosely and relatively widely separated in the bath. 25

SVERRE GULBRANDSEN.
